Primary Examiner — Robin V Webster*Assistant Examiner* — Rachel Voorhies(74) *Attorney, Agent, or Firm* — Paul D. Bianco; Lourdes Perez; Fleit Gibbons Gutman Bongini & Bianco PL(57) **CLAIM**

The ornamental design for a paint spray gun with pattern, as shown and described.

DESCRIPTION

FIG. 1 is a first side view of a paint spray gun with pattern according to the present invention;

FIG. 2 is a second side view of the paint spray gun with pattern of FIG. 1;

FIG. 3 is a front view of the paint spray gun with pattern of FIG. 1;

FIG. 4 is a back view of the paint spray gun with pattern of FIG. 1; and,

FIG. 5 is a perspective view of the paint spray gun with pattern of FIG. 1.

The broken lines in the drawing illustrate portions of the paint spray gun which form no part of the claimed design.
